(57) **CLAIM**
The ornamental design for a bandage cutter, as shown and described.

DESCRIPTION

FIG. 1 is a perspective view of a bandage cutter embodying our new design.

FIG. 2 is another perspective view thereof.

FIG. 3 is a front view thereof.

FIG. 4 is a back view thereof.

FIG. 5 is a bottom view thereof.

FIG. 6 is a top view thereof.

FIG. 7 is a side view thereof; and,

FIG. 8 is an opposite side view thereof.

The design is for a cutter which is used to cut medical bandages.
